Patented Sept. 10, 1963

196,276

PHOTOGRAPHIC MICRODENSITOMETER

Victor Italiano, Binghamton, N.Y., assignor to General
Aniline & Film Corporation, New York, N.Y., a cor-
poration of Delaware

Filed Jan. 17, 1962, Ser. No. 68,346

Term of patent 14 years

(Cl. D61—1)

FIG. I

Des. 196,276

PAGE 2

FIG. 4

FIG. 3

FIG. 1 is a perspective view of a photographic microdensitometer, showing my new design;

FIG. 2 is a rear perspective view thereof;

FIG. 3 is a front elevational view thereof; and

FIG. 4 is a side elevational view thereof.

I claim:

The ornamental design for a photographic microdensitometer, substantially as shown.
